Des. 225,116
Patented Nov. 14, 1972

225,116

COMBINED PAINT BOX STAND AND EASEL

Alexander Krajeski, 2401 Laurel Pass,
Hollywood, Calif. 90046

Filed Nov. 4, 1969, Ser. No. 19,924

Term of patent 14 years

Int. Cl. D6—06

U.S. Cl. D29—20

Fig. 2.

FIG. 1 is a front perspective view of a combined paint box stand and easel showing my new design; and

FIG. 2 is a rear perspective view.

I claim:

The ornamental design for a combined paint box stand and easel, as shown.
